[57] **CLAIM**

The ornamental design for a holder for plants, flowers,
radios, or the like, as shown.

DESCRIPTION

FIG. 1 is a top, rear and side perspective view of a
holder for plants, flowers, radios, or the like, showing
my new design;

FIG. 2 is a top plan view thereof;

FIG. 3 is a right side elevational view thereof, the left
side being a mirror image;

FIG. 4 is a rear elevational view thereof;

FIG. 5 is a front elevational view thereof; and

FIG. 6 is a bottom plan view thereof.

*FIG. 1**FIG. 2*FIG. 4

FIG. 3

FIG. 6
